Primary Examiner — Elizabeth J Oswecki(74) *Attorney, Agent, or Firm* — Sughrue Mion, PLLC(57) **CLAIM**

The ornamental design for a chip, as shown and described.

DESCRIPTION

FIG. 1 is a perspective view of the chip, showing our new design;

FIG. 2 is a top view thereof;

FIG. 3 is a bottom view thereof;

FIG. 4 is a front view thereof;

FIG. 5 is a rear view thereof;

FIG. 6 is a left side view thereof; and,

FIG. 7 is a right side view thereof.

The broken lines shown in the drawings represent portions of the chip that form no part of the claimed design.
